UNITED STATES PATENT OFFICE.

LEANDER K. BINGHAM, OF NEW YORK, N. Y.

APPARATUS FOR MAKING PRINTERS' ROLLERS.

SPECIFICATION forming part of Letters Patent No. 413,893, dated October 29, 1889.

Application filed March 1, 1889. Serial No. 301,668. (No model.)

To all whom it may concern:

Be it known that I, LEANDER K. BINGHAM, a citizen of the United States, residing at New York, in the county of New York and State of New York, have invented certain new and useful Improvements in Apparatus for Making Printers' Rollers; and I do declare the following to be a full, clear, and exact description of the invention, such as will enable others skilled in the art to which it appertains to make and use the same, reference being had to the accompanying drawings, and to the letters of reference marked thereon, which form a part of this specification.

Figure 1 is a top view, partly broken away, to show the bottom of an apparatus in which the present invention is displayed. Fig. 2 is a detail showing a top view of the invention. Fig. 3 is a section on line $\alpha\alpha$, Fig. 2. Fig. 4 is a modification. Fig. 5 is a perspective of the spider.

This invention relates to improvements in apparatus for making printers' rollers, more especially to that kind where a cylinder holds a number of mold-tubes and the bottom turns under the cylinder or the cylinder above the bottom. In this kind of apparatus the bottom is usually provided with an open gutter, as shown at A in the drawings. This gutter is provided with a nozzle α , through which roller-composition is admitted. The mold-tubes B are arranged in radial sets, as shown. By rotating the cylinder or the bottom the gutter A is brought under the bottoms of each set of mold-tubes, and they are filled by the composition entering the nozzle α into the gutter A and up into the mold-tubes. The roller-stocks are inserted in the mold-tubes, their ends being placed in centering-spiders. Now it is found that as the gutter comes under the ends of these stocks either part of the spiders

or the projecting ends of the roller-stocks drop down into the gutter, and hence prevent or impede the proper rotation of the device.

It is the object of the present invention to cure this defect. This is done by placing bridges across the gutter in the paths of the mold-tubes.

In the annexed drawings, the letter A indicates the gutter, and B the mold-tubes. Across the gutter are placed in the paths of the mold-tubes bridges C. These may be separate pieces riveted to the bottom, as shown in Fig. 2, or they may be cast with the bottom, as shown in Fig. 4. The former is perhaps preferable, as they can be regulated to suit the spacing of the mold-tubes.

The form of spider shown in Fig. 5 is perhaps the preferable form to use with this device. In use the lower ends of the roller-stocks rest in these spiders, as usual, the spiders being at the bottoms of the mold-tubes. Now, when the bottom is turned under the cylinder or the latter above the former, as the mold-tubes come to the gutter the spider rests across the bridges, without any danger of dropping into the gutter or danger of the end of the roller-stock getting caught therein. Upon further rotation the mold-tubes pass away from the gutter readily.

Having described my invention, what I claim is—

The combination of the cylinder and its mold-tubes with a bottom having a gutter across which there are several bridges in the paths of the mold-tubes, as set forth.

In testimony whereof I affix my signature in presence of two witnesses.

LEANDER K. BINGHAM.
